Application July 21, 1953, Serial No. 26,063

Term of patent 7 years

(Cl. D3—26)

To all whom it may concern:

Be it known that I, Herma Wiedle Dozier, a citizen of the United States and a resident of St. Louis, county of St. Louis, and State of Missouri, have invented a new, original, and ornamental Design for an Open-Front Maternity Slip, of which the following is a specification, reference being had to the accompanying drawings, forming part hereof and in which:

Fig. 1 is a front perspective view of an open-front maternity slip showing my new design.

Fig. 2 is a similar front perspective view with the apron lifted, showing the front opening.

Fig. 3 is a rear view thereof.

I claim:

The ornamental design for an open-front maternity slip, substantially as shown.
